YARN TWISTING MACHINE

Jack K. Hartley, Queensferry, near Chester, England, and Vernon F. West and Thomas E. Edwards, Flint, Wales, assignors to Courtaulds Limited, London, England, a British company

Application April 11, 1951, Serial No. 220,412
In Great Britain May 19, 1950

4 Claims. (Cl. 57—58)

1

This invention relates to yarn twisting machines and in particular to such machines having double-twist spindles.

The customary form of double-twist spindle includes a carrier for a yarn holder such as a bobbin from which the yarn to be twisted is withdrawn, a hollow live spindle on which the bobbin carrier is freely mounted and down through which the yarn on withdrawal from the bobbin is passed, and a rotating cup which surrounds the lower end of the bobbin carrier and below which the yarn is withdrawn from inside the hollow spindle and is then passed as a balloon to a separate yarn collector. It is customary, but not essential, to provide a rotatable flyer at the top of the bobbin so that the yarn is passed from the bobbin, through the flyer and then into the hollow spindle.

In such double-twist spindles it is necessary to maintain the carrier stationary during normal operations. In one type of spindle, the spindle is canted and a weight, for example of lead, is eccentrically mounted within the carrier. This method is not entirely satisfactory since parts of the spindle are not readily accessible and, should abnormal conditions arise causing the carrier to rotate, the high speeds and weights involved render such rotation dangerous as parts may fly off and cause damage to operatives and neighbouring machinery. In United States patent specification No. 2,482,654 it has been proposed to obviate this difficulty by causing both the double-twist spindle and the take-up spool to stop automatically when the carrier rotates, the rotation of the carrier causing a coil spring to be thrown by centrifugal force into the ballooning yarn and so breaking the yarn and operating mechanism whereby the double-twist spindle slides away from its driving belt and the take-up spool is lifted from its driving wheel.

It is also known to mount the double-twist spindle vertically and to maintain the carrier stationary by electrically or magnetically controlled devices. With such vertical spindles it is also known, see for example British patent specifications Nos. 299,860 and 590,182, to use the controlled device to operate a stop mechanism should the carrier be caused to rotate.

When the yarn in a double-twisting machine breaks, either as a result of the carrier rotating or for any other reason, the continued rotation of either the double-twist spindle or the collecting device, or both, causes the broken yarn to lap round moving parts of the machine; consequently it usually takes a long time for the oper-

2

ator to locate and unravel the broken ends and piece them up preparatory to restarting the machine.

The object of the present invention is to expedite the piecing-up operation with vertical double-twist spindles.

According to the present invention, a yarn twisting machine comprises a double-twist spindle pivoted at its lower end and so mounted that when free it falls forward into a non-operative position, a collector for the twisted yarn, a yarn break detector, and catch mechanism for holding the double-twist spindle in a vertical driving position and releasing it at the instigation of the yarn break detector. In accordance with the invention, the yarn break detector may also initiate the release of the yarn collector from its drive.

In a preferred form of machine according to the invention, the yarn collector comprises a pivoted cradle for holding a cheese or like package which is surface driven by a driving roller and the yarn break detector comprises a floating lappet pivoted on the front of the cradle and provided with a member which on the release of the lappet cooperates with a cam on the shaft of the driving roller to raise the front of the cradle and in so doing to release the cheese or the like from the driving roller and also to release the catch of the double-twist spindle which latter consequently falls forward into the non-operative position. Thus, as the cradles rises, its rear end may depress one arm of a see-saw the other arm of which carries one end of a Bowden wire operatively connected to the catch holding the double-twist spindle in the vertical driving position. Alternatively the catch of the double-twist spindle may be released by means of a solenoid which is energised through the movement of the floating lappet on yarn breakage.

The machine according to the invention may also include a snap catch for holding the cradle in the inoperative position, a readily accessible release handle being provided for use in restarting.

In order to stop the cam on the shaft of the driving roller continually knocking the cooperating member of the floating lappet after the cradle has been lifted, the lappet is preferably automatically swung over to an idle position once the double-twist spindle has been released. This may be effected by fitting on the lappet a bell crank lever one arm of which carries a balance-weight, such that when the lappet is re-

leased and its member comes into contact with the cam, the weighted arm of the bell-crank lever moves and compresses a leaf spring and once the cradle has been raised and the cam is no longer in contact with the member, the tension in the leaf spring is released and causes the lappet to swing over and move the lappet member out of the way of the still rotating cam.

In the machine according to the invention, the carrier is preferably held stationary by means of the magnetic control, preferably of the type described and claimed in the specification of British application No. 21,392/49, so that when the carrier rotates under abnormal conditions, a member of magnetic or magnetisable material is drawn by a magnet within the cup into the ballooning yarn so that the yarn is broken and the catch mechanism for the double-twist spindle is released.

A machine constructed according to the invention is illustrated by way of example in the accompanying drawings in which:

Figure 1 is a front elevation of a double-twist spindle and a collecting device.

Figure 2 is a side elevation of the double-twist spindle and the collecting device shown in Figure 1.

Figures 3 to 6 are diagrammatical representations of various positions of the mechanism for releasing the collecting device and the double-twist spindle from their respective drives, Figure 3 showing the operative position, Figure 4 showing the position when releasing is about to be initiated, Figure 5 showing the cradle of the collecting device in the lifted position and Figure 6 showing the final inoperative position.

Figure 7 is a plan view of the release catch for the double-twist spindle, and

Figure 8 is a side elevation of the double-twist spindle in the inoperative position.

Referring to Figures 1 and 2, a yarn 1 drawn from a bobbin 2 passes through a yarn tensioning device 3 and down a hollow spindle 4 on which the bobbin 2 is freely mounted; the yarn 1 then passes from the hollow spindle 4 into a thread-storage groove 5 and as a balloon 6 to a pigtail guide 7 mounted centrally above the spindle 4. From the pigtail guide 7 the yarn 1 passes over a horizontal glass rod 8 and thence horizontally to a traversing guide 9 which winds it on a cheese 10. The cheese 10 is held within a pivoted cradle 11 such that it is normally kept in contact with a drive roll 12 by its own weight.

A floating lappet generally indicated at 13 and conveniently made of round wire, in the form of a bell-crank lever is pivoted at its angle to the cradle 11 and has a short arm 14, recessed at its end, and a long arm 15. A second arm 16 similar to the arm 15 is pivoted to the cradle 11 at the other end of the cheese 10 and a horizontal wire 17 between the ends of the arms 15, 16 is normally supported by the yarn 1 as it passes from the glass rod 8 to the traversing guide 9. An adjustable balance weight 18 sliding on a bar 19 fixed to the second arm 16 to form a bell-crank lever is adjusted so that the pressure of the wire 17 on the yarn 1 is a minimum.

The double-twist spindle is mounted on a cradle 28 about a pivot 29 and is normally held vertical by means of a catch 27. In the vertical position, a driving belt 30 is in contact with a wharf 31 and a horse shoe magnet 32 is mounted on the cradle 28 with its poles in opposition to the poles of a similar magnet (not shown) within the bobbin carrier of the spindle to prevent the bobbin 2 from rotating during normal operations.

If the yarn 1 should break, the wire 17 is no longer supported by the yarn 1 as shown in Figure 3 and the lappet 13 swings in an anti-clockwise direction to initiate the stop mechanism as follows:

The short arm 14 falls into the path of a cam 20 fixed to the end of the driving shaft of the drive roll 12 (Figure 4) so that a lug 21 on the cam 20 forces the arm 14 upwards and consequently causes the cheese 10 to be lifted away from the drive roll 12 until the cradle 11, moving about its pivot 11A, is held at its right-hand end by a catch 22. The cheese 10 remains out of contact with the drive roll 12 until the catch 22 is released manually by a lever 23 (Figure 2). As the cradle 11 is lifted it depresses one end of a see-saw rod 24 which is pivoted at its middle and is attached to a Bowden cable 25 at its other end. The Bowden cable 25 is connected to the catch 21 and when the see-saw rod 24 is tilted (Figure 5) the catch 21 is released against a spring 27A (Figure 7). When the catch 21 is released the cradle 28 is also released so that the spindle falls forward about the pivot 29, away from the driving belt 30 until the wharf 31 comes into contact with a brake shoe 33 (Figure 8).

When the lappet 13 falls, the bar 19 comes into contact with a leaf spring 26 which is compressed as the cradle 11 is lifted. As soon as the short arm 14 is released by the cam lug 21, the leaf spring 26 flicks the bar 19 and the lappet 13 in a clockwise direction to the position shown in Figure 6 so that further contact of the arm 14 with the cam 20 is prevented until the mechanism is reset. The double-twist spindle is reset by a handle 34 mounted on the cradle 28, the cradle 28 being centrally held about its pivot by two centering springs 28A.

What we claim is:

1. A yarn twisting machine comprising a double twist spindle pivoted at its lower end and so mounted that when free it falls forward to a non-operative position, a collector for the twisted yarn, a yarn break detector and catch mechanism for holding the double twist spindle in a vertical driving position and releasing it at the instigation of the yarn break detector.

2. A yarn twisting machine comprising a double twist spindle pivoted at its lower end and so mounted that when free it falls forward to a non-operative position, a collector for the twisted yarn, a yarn break detector, catch mechanism for holding the double twist spindle in a vertical driving position and releasing it at the instigation of the yarn break detector and release mechanism for removing the yarn collector from its drive, also at the instigation of the yarn break detector.

3. A yarn twisting machine comprising a double twist spindle pivoted at its lower end and so mounted that when free it falls forward to a non-operative position, a collector for the twisted yarn comprising a pivoted cradle for holding the yarn package, a driving shaft, a roller mounted on the said shaft to drive the yarn package by surface contact, a cam having a lug mounted on one end of the driving shaft, a yarn break detector comprising a floating lappet pivoted on the front of the said cradle, catch mechanism for holding the double twist spindle in a vertical driving position, the arrangement being such that the floating lappet is normally supported by the yarn but that when a yarn breaks, the lappet swings about its pivot into the path of the lug on the cam which thereby lifts the cradle out of contact with the driving roller and at the same time releases

the catch mechanism so that the double twist spindle falls forward to the inoperative position.

4. A machine as claimed in claim 3 wherein the catch mechanism comprises a see-saw and a Bowden wire connected at one end to the catch holding the double twist spindle vertical and at the other end to one arm of the see saw, the said catch mechanism being operated when yarn breakage

occurs by the rising cradle depressing the arm of the see saw and so lifting the arm connected to the Bowden wire and releasing the catch of the double twist spindle.
